UNITED STATES PATENT OFFICE

109,940

DESIGN FOR AN ICE CREAM CONE

Michael A. Pecora, West Hazleton, Pa.

Application January 22, 1938, Serial No. 74,473

Term of patent 14 years

To all whom it may concern:

Be it known that I, Michael A. Pecora, a citizen of the United States and resident of West Hazleton, county of Luzerne, and State of Pennsylvania, have invented a new, original, and ornamental Design for Ice Cream Cones, of which the following is a specification, reference being had to the accompanying drawing forming a part thereof.

Fig. 1 is a perspective view of the ice cream cone as taken from one side thereof showing my new design.

Fig. 2 is a similar view as taken from the opposite side thereof.

Fig. 3 is a plan view thereof.

Fig. 4 is a side elevational view thereof.

The ice cream cone is substantially of conical configuration having its lower exterior area decorated with perpendicular ornamentalations and its upper extremity provided with a rim, that area between the perpendicular ornamentalations and the rim being formed to represent a human head, the faces of which are disposed on opposite sides of the ice cream cone.

I claim:

The ornamental design for an ice cream cone as shown and described.

MICHAEL A. PECORA.
